(57) **CLAIM**

The ornamental design for an LED lamp, as shown and described.

DESCRIPTION

FIG. 1 is a perspective view of the LED lamp showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 2;

FIG. 11 is a partial enlarged view of portion 11 in FIG. 2; and,

FIG. 12 is a partial enlarged view of portion 10 in FIG. 3. The broken lines depict portions of the LED lamp in which the design is embodied that form no part of the claimed design. The dot-dash broken lines annotate boundaries of the enlarged views and form no part of the claimed design.
